UNITED STATES PATENT OFFICE

JOSEPH J. MARIOTTI, OF CHICAGO, ILLINOIS, ASSIGNOR TO DAPRATO STATUARY COMPANY, OF CHICAGO, ILLINOIS, A CORPORATION OF ILLINOIS

DOOR OPERATING MECHANISM

Application filed March 12, 1930. Serial No. 435,075.

This application relates to improvements in constructions of doors, gates, and the like, and operating mechanism therefore, and pertains particularly to apparatus for closing half of a double door or gate in advance of the other and likewise for causing one half of a double door or gate to open in advance of the other half.

When the adjacent edges of double doors are constructed to meet on an angle oblique to the plane of the doors, or when an overlapping weather strip is applied on one of the doors, necessarily one door must be opened in advance of the other and closed later than the other to prevent jamming of the doors. For example, in the construction herein shown the two halves of the double gate meet on a curved surface which is generally oblique to the faces of the gates. It is an object of this invention to provide an operating mechanism for causing the two such halves of the gate or door to be rotated when one of them alone is grasped and swung while assuring that the gates will swing in the proper sequence when opening or closing to prevent jamming.

Another object of this invention is to provide a closing and opening mechanism for closure members such as gates, doors, hinged windows, and the like, which enables an operator to retain positive control of both halves of the closure member during the opening and closing thereof.

Other objects, advantages and capabilities of the invention which are inherently possessed by it will become apparent upon perusal of this specification and the attached drawings.

The embodiment disclosed in the drawings comprises a pair of hinged gates, but it should be understood that this construction and mechanism may be applied equally as well to doors of various kinds, to windows and other closure members, and that instead of having the particular joint shown at the middle of these gates some other angle of joinder could be employed or a weather strip cleat could obviously be placed on either door to seal the junction of the two doors.

In the drawings, Fig. 1 is a top plan view of a pair of gates in closed position, and

showing in dotted line the position of the gates when wide open.

Fig. 2 is a front elevation of the same gates.

Fig. 3 is a plan section looking downwardly into the box which contains the operating mechanism, showing the mechanism as it appears when the gates are closed.

Fig. 4 is a similar view of the same mechanism as it appears when one gate has been partially opened and the other gate is about to commence its opening movement.

Fig. 5 is a partial elevation of the gate and a vertical sectional view of the gate operating mechanism.

Fig. 6 is an enlarged sectional view of the bearing and gear construction for the left hand gate.

Fig. 7 is an enlarged detailed view of an interlocking projection and notch shown in Figs. 3 and 4.

Fig. 8 is an enlarged detailed view of a combined guide and bearing for the two reach rods.

Fig. 9 is an enlarged view of the assembly of the spur gear and rack.

In the drawings the left gate 1 is shown provided with a top hinge pintle 2 which is guided in the arm 3, the latter being anchored in the post 4 to a vertical pin 5. This manner of mounting the top hinge pintle is preferred in ornamental stone construction where a heavy gate such as a marble or bronze gate must be carried on an ornamental stone post. The bottom hinge pintle for gate 1 is indicated by the numeral 6 and is connected with the gate by means of a bracket 7 bolted thereto. This hinge pintle 6 extends through the brackets 7 through a lateral thrust bearing generally indicated as 8. Dust is prevented from entering the thrust bearing by means of a collar 9 which fits snugly thereabout.

The thrust bearing 8 is carried in a block 11, the latter being bolted by means of the bolt 12 or any other suitable means, to the inside of a box 13. The box 13 extends longitudinally of the gates and will be buried below the surface over which the gates move. In some installations this box would be buried in concrete. The hinge pintle 6 extending

through the block 11 has mounted on it a spur gear 14 which is keyed thereto by a key 15. Just below the spur gear there is provided a split washer 16 and in the aperture provided in this washer a smaller key 17 is seated and is secured to the spur gear by means of the screw 18. A large part of the weight of this gate is carried through the hinge pintle 6 and split washer 16 upon a bottom vertical thrust bearing 19 and is guided in its rotative movement by a second lateral thrust bearing 21. The latter two bearings are carried in a block 22 which is secured to the bottom of the box 13 in any suitable manner; for example, as by the screws 23.

The spur gear 14 is in constant mesh with a rack 24, the latter being secured by means of bolts 25 and 26 to a reach rod 27 which extends longitudinally of the housing or box 13.

The reach rod 27 extends through a combined guide and bearing shown in Fig. 8 and there indicated with a numeral 28. This bearing is clamped to the reach rod 27 by means of a plate 29 and screws 31 and 32. A second reach rod 33 connected with the other gate has a slightly smaller dimension where it passes through this bearing, as shown in Fig. 8, and hence may slide relatively to the reach rod 27 and to the bearing 28 and clamping plate 29.

The right hand gate 34 is provided with the same type of mounting for its top hinge pintle as is the left hand gate, hence the description will not be duplicated. The right hand gate is provided with a bottom hinge pintle 35 mounted in a similar bearing as that which has just been described and which is clearly shown in Fig. 6. However, the spur gear 36 provided on the right hand gate is of a smaller diameter than that provided on the left hand gate for the purpose of causing the right hand gate to rotate at a higher rate of speed than does the other gate. A rack 37 meshes with the spur gear 36 and is rigidly connected in any suitable manner to the reach rod 33. A combined bearing and guide generally indicated as 38 constructed like the guide 28 is provided to guide the movement of the reach rods. The bearing 38 may be clamped to either rod as may be desired and allow the other rod to slide freely through.

In view of the manner of joining the two gates, as shown in Fig. 3, the left hand gate must be opened first. This will be done manually by pulling or pushing the gate and as the left gate moves into the dotted line position shown in Fig. 4 its spur gear 14 will cause the rack 24 to slide to the left. The projection 41 on the reach rod 27 will slide to the left in the notch 42, with which the reach rod 33 is provided, until the projection strikes the left end of the notch 42 whereupon further opening of the left gate

will cause the reach rod 33 to be pulled toward the left and to cause the rack 37 to swing the gate 34 open. Fig. 4 shows the position of the parts just at the instant the projection 41 has struck the left end of the notch 42. Any further opening of the left gate will not only move the reach rod 33 to the left and open the right hand gate but at the same time a locking bar 43, which swings about a pivot 44, will be pushed by a compression spring 45 into parallel relation with the two reach rods whereupon the shoulder 46 on this locking bar will drop into snug fit in front of a shoulder 47 which is provided at the end of a plate 48 secured on the surface of the reach rod 33. With the parts in position shown in Fig. 4 this locking bar is unable to swing into locking position because the outer end 49 of the locking bar is still riding on a cam 51, the latter being mounted immovably in the housing or box 13.

Further opening of the left hand gate beyond the dotted line position shown in Fig. 4 will cause the right hand gate to swing open, the latter moving at a higher rate of speed because of the use of its smaller spur gear. The spur gears are so designed that by the time the left hand gate is in full open position the right hand gate will have caught up with it and be likewise in full open position.

During the longitudinal sliding of the two reach rods they are allowed to bear vertically downwardly against rollers 39 which are mounted in the housing.

Whenever it is desired to close the gates either gate may be grasped manually and swung toward closed position. The locking bar 43 will positively assure that the rotation of either gate will cause the other gate to likewise rotate. During the closing movement the right hand gate will naturally move more rapidly and will be almost in closed position, just prior to the time that the locking bar 43 which is now moving toward the right, as viewed in Fig. 4, strikes the cam 51 and is thus kicked out of locking position. If the operator is at that time pushing the right hand gate he can thus push it to full closed position moving the left hand gate into the dotted line position shown in Fig. 4. From this point the left hand gate must now be closed by the operator grasping it alone and pushing it to closed position. As he does so, the locking bar 43 rides further up onto the cam 51 and assumes the position shown in Fig. 3. At the same time the projection 41 then moves to the right end of the slot 42.

To prevent undesirable friction between the compression spring 45 and the locking bar 43 as the latter moves, the bracket 45', which carries the compression spring, is secured by screws or any other suitable means to the reach rod 27 so that it may move there-

with just as the locking bar itself moves with the reach rod 27 to which it is pivoted. Figs. 3 and 4 show that the spring has been moved toward the left during the initial movement of the reach rod.

It may now be understood that both gates may be opened by initially pulling the left gate into the position shown in Fig. 4 and thereafter pulling either gate open to thus accomplish the opening of both gates and that both gates may be returned to the position shown in Fig. 4 by pushing or pulling on either of them. The gates are thus opened and closed in the proper sequence to prevent jamming and a very tight fit of the abutting surfaces of the two gates may be thus employed without interfering with the gate operation. This feature is of great importance when employed in doors and windows, and contributes to the appearance of a gate construction such as is here illustrated.

It should be understood that the embodiment of the invention herewith shown has been selected for the purpose of illustrating the invention in one of its practical forms, and that various modifications of the invention may be devised, which will employ its principles and remain within the scope of the invention.

Having shown and described the invention, I claim:

1. In an operating mechanism for a pair of pivoted closure members, means connected with both members when the latter are open for causing the closing rotation of one member to rotate the other to closed position before the first member reaches closed position together with means for operatively disconnecting the first said means after the second member reaches closed position.

2. In an operating mechanism for a pair of pivoted closure members, means including bars connected with both members and with each other when the members are open for causing the closing rotation of one member to rotate the other to closed position before the first member reaches closed position, together with means for operatively disconnecting said bars from each other after the second member reaches closed position.

3. In an operating mechanism for a pair of pivoted closure members, means connected with both members when the latter are open for causing the closing rotation of either member to rotate the other toward closed position, means operatively connected with the first means for causing the members to rotate at unequal speeds, and means for operatively disconnecting said members automatically before both reach closed position.

4. In an operating mechanism for a pair of pivoted closure members, means connected with both members when the latter are open for causing the closing rotation of either member to rotate the other toward closed

position including means for causing the members to rotate at unequal speeds together with means for operatively disconnecting said members automatically before both reach closed position.

5. In an operating mechanism for a pair of pivoted closure members, a spur gear connected with each member and a rack and rack bar operatively associated with each gear and member, mid bars being slidable relatively to each other while one member is closed and the other member is within a predetermined angle from closed position, and means for automatically connecting said bars in non-slidable relation whenever the second member opens beyond said angle.

6. In an operating mechanism for a pair of pivoted closure members, a gear on each member and a rack and rack bar operatively associated with each gear, said gears being of unequal diameter, and means for automatically connecting said bars together to effect simultaneous rotation of both members during opening movement of both members and beyond a predetermined angular position of one of them.

7. In combination with a pair of closure members, meshed gears and racks provided for each of the pair respectively, rack bars connected respectively with mid racks and slidable relative to each other when both members are closed, and means for automatically locking the bars in non-slidable relative arrangement when one member has been opened to a predetermined angular position while the other is still closed.

8. In combination with a pair of closure members, a meshed gear and rack provided for each of said members, rack bars connected with said racks and connected to each other in non-slidable relation when said members are open for causing either member to rotate when the other rotates, and means operated by the closing of said member for effecting a relatively slidable arrangement of the bars to enable one member to thereafter be rotated without rotating the other.

9. In combination with a pair of closure members, a gear connected with each member in mesh with a slidable rack for each member, rack bars connected with each rack respectively and disposed slidably relative to each other when both members are closed, a notch provided in one rack bar and a projection on the other rack bar slidably disposed in the notch and means cooperating with said notch and projection when one closure member is open beyond a predetermined angular position for locking the two rack bars in non-slidable relative arrangement.

10. In combination with a pair of closure members, a gear connected with each member and in mesh with a separate slidable rack, means including a locking bar for automatically locking the two racks in non-slidable

relative arrangement when one closure member has been opened beyond a predetermined angular position for causing simultaneous rotation of both members upon further opening movement of the first said member, said means being constructed to actuate said locking bar during the closing of said members to unlock the rack bars.

11. In an operating mechanism for a pair of pivoted closure members, means including bars operatively connected with both members and with each other when both members are fully opened and constructed for causing rotation of one member to rotate the other to closed position before the first reaches closed position, said bars being operatively disconnected when both members are closed.

In witness of the foregoing I affix my signature.
